(57) **CLAIM**

The ornamental design for a smart phone back protector with ring holder, as shown and described.

DESCRIPTION

FIG. 1 is a rear perspective view of a smart phone back protector with ring holder showing my new design therefor;
FIG. 2 is a rear elevational view thereof;
FIG. 3 is a front elevational view thereof;
FIG. 4 is a right side elevational view thereof;
FIG. 5 is a left side elevational view thereof;
FIG. 6 is a top plan view thereof; and,
FIG. 7 is a bottom plan view thereof.
Throughout the drawings, broken lines indicate environment and form no part of the design

1 Claim, 5 Drawing Sheets
